UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 13,374, dated October 31, 1882.

Application filed August 11, 1882. Term of patent 3½ years.

To all whom it may concern:

Be it known that I, OTTO HEINIGKE, of New Utrecht, in the State of New York, have invented a new and original Design for Carpets, 5 of which the following is a specification.

This invention relates to a new and original design for carpets and similar fabrics; and it consists in the novel grouping and configuration of figures hereinafter more fully described.

10 The accompanying photograph illustrates a face view of a carpet having my new design.

A is a broad inner band having a narrow strip along its inner edge, ornamented with small running figures, and a broad field partly 15 traversed by spreading leaves and leaf sprays, and partly by squares having variegated small ornamental work.

B is a broad outer band completing the border design, and consisting of several smaller

bands ornamented variously, as shown in the 20 accompanying photograph, with a series of ornamental half-squares, with small leaf sprays and flower clusters disposed over a blank field, and with symmetrically-arranged sprays and arch-like and cross-like figures. 25

I claim—

1. The design for carpets, consisting of the band A, substantially as shown.
2. The design for carpets, consisting of the band B, substantially as shown.
3. The design for carpets, consisting of the bands A and B, substantially as shown and described.

OTTO HEINIGKE.
